WINDOW WASHING CHAIR

Valentine Filipich, Linden, N. J.

Application September 14, 1934, Serial No. 744,049

1 Claim. (Cl. 304—24)

This invention relates to that class of inventions having to do with scaffolds, seats, chairs and the like expressly designed and used by painters and window-washers to expedite safe completion of an appointed task.

Being generally conversant with the state of the prior art to which the invention relates, I am admittedly aware of the fact that various types of seats and chairs have been designed and adapted for use to promote expeditious and safe window washing. It follows, therefore, that it is my primary aim to generally improve upon these previously known structures by providing one characterized by structural refinements and distinctions calculated to provide appreciable improvements such as transcend the prior structures and in so doing to promote economy, efficiency, stability and safety.

Briefly stated, the preferred embodiment of the invention is characterized by the incorporation therein of an appropriately shaped seat board designed for dependability and comfort, said seat board being equipped with a foldable back-rest for compactness and convenience, and further provided with complemental adaptation and fastening means aptly fitted for maintaining the chair in an adequate manner on the window sill.

Other features and advantages will become more readily apparent from the following description and the accompanying illustrative drawings.

In the drawings, wherein like numerals are employed to designate like parts throughout the same:

Fig. 1 is an elevational view of the improved occupant chair illustrating the preferred construction and the manner in which it is attached.

Fig. 2 is an elevational view with the chair detached from the window sill and showing the back-rest folded down to collapsed position.

Fig. 3 is a front view of the structure illustrated in Fig. 1, the chair being removed from the window.

Fig. 4 is a top plan view illustrating principally the construction and design of the seat board and the clamping or retention means.

Fig. 5 is a transverse detail sectional view through the plate portion of the adapter or clamping bracket, the section being taken on the plane of the line 5—5 of Fig. 4.

Fig. 6 is a detail perspective view of an especially designed stabilizing clamping member.

Fig. 7 is a longitudinal sectional view on an

enlarged scale, taken approximately on the plane of the line 7—7 of Fig. 4.

Referring now to the drawings by distinguishing reference numerals, it will be observed in Fig. 1 that the window frame is denoted as a unit by the numeral 8 and the stepped window sill is distinguished by the numeral 9. The chair is so constructed as to adapt it to fit this stepped or conventional type window sill.

The seat board of the improved chair is denoted by the numeral 10 and is of appropriate proportions and material. It is here shown as being in the form of a saddle and the rear end or cantile portion is provided at opposite corners with keeper notches 11. The central forward extension 12 which may be distinguished as the pommel is of suitable narrowed configuration and terminates in a straight-cut end 13 which constitutes an abutment and is designed to rest against the ledge portion in the angle 9a of the window sill in the manner shown in Fig. 1. Hence, this extension constitutes a stabilizing pommel as well as a carrier for the clamping means.

The clamping and retaining means which cooperates with the extension or cantile 12 comprises essentially a hanger unit including a rectangular adapter plate 14 terminating in a padded hook 15 to engage over the ledge of the window sill as shown in Fig. 1. As indicated in Fig. 30 5, the adapter plate which is longitudinally elongated and rectangular is formed with a longitudinal central slot 16 to accommodate the threaded end of the bolt 17 carried by the pommel 12. On opposite sides of this slot, I provide 35 spaced parallel teeth 18 which may be described as retaining or rack teeth. The thumb nut 19 on the threaded end of the bolt is adapted to cooperate with a ratchet plate 20. This ratchet plate is of suitable proportions and preferably 40 square and provided on its bottom with ratchet teeth 21 to engage adjustably with the rack teeth 18. In addition, there is a central aperture in the plate to accommodate the bolt and nut and in alignment with this are depending lugs or 45 detents 22 which serve as stabilizing and guide fingers and which slide in the longitudinal slot 16. It is evident therefore that this hooked adapter unit makes it possible to fit the seat board to window sills of varying proportions. It 50 is observed that the hook lies in a plane to cooperate efficiently with the abutment or terminal 13 of the extension 12.

On the bottom of the seat board, I provide a pair of companion or complemental stabilizing 55

cleats 23. These are in the form of vertically disposed wooden cleats, the lower edges 23 are inclined to conform to and rest in a solid manner upon the adjacent surface of the stepped part 8 of the window sill as shown in Fig. 1. The inner ends 25 serve as rests and engage firmly behind the angular shoulder 9b on the window sill. This makes for rigidity and safety of maintenance of the seat board. In other words, it also provides 10 for balance and stability and insures expeditious application and effective maintenance.

The next part of the structure to be observed is the back rest 26. This is in the form of an appropriately shaped and proportioned frame 15 which includes vertical end members or frame pieces 27 which are attached by hinges 28 to the seat board which have their lower end portions extending down into the keeper notches 11. With this arrangement, it is evident that a 20 comfortable seat and back rest is provided for the user or occupant. Then too, when the device is not in use, the back rest can be folded down against the seat board as shown in Fig. 2 to provide for compactness and convenience in 25 handling, shipping and storage.

Admittedly, although there are no radical structural differences in the device herein illustrated, there are certain evident improvements and refinements which, it is believed, warrant 30 favorable reception by the trade and unqualified endorsement by the average user.

It is thought that persons skilled in the art to which the invention relates will be able to obtain a clear understanding of the invention after considering the description in connection with the drawings. Therefore, a more lengthy 5 description is regarded as unnecessary.

Minor changes in shape, size and rearrangement of details coming within the field of invention claimed may be resorted to in actual 10 practice, if desired.

I claim:

In a structure of the class described, a seat board, a hinged back rest attached thereto, said seat board being formed on its forward edge with an extension constituting a pommel and 15 clamp carrier, a clamp unit on the upper face of the pommel and including an attaching hook and a slotted adapter plate, a bolt carried by said pommel and including a nut co-operable with said slotted adapter plate, and a pair of 20 reinforcing cleats on the underside of said seat board, said cleats terminating short of said extension, said adapter plate being formed on opposite sides of the slot with rack teeth, and a ratchet plate superimposed on said adapter plate 25 and including lugs slidable in said slot and ratchet teeth co-operable with said rack teeth, said ratchet plate being further co-operable with said bolt.

VALENTINE FILIPICH. 30
